(57) **CLAIM**

The ornamental design for circular seed distribution manifold, as shown and described.

DESCRIPTION

FIG. 1 is an upper perspective view of a circular seed distribution manifold design according to the present invention.

FIG. 2 is a lower perspective view of the circular seed distribution manifold design shown in FIG. 1.

FIG. 3 is a side elevation view of the circular seed distribution manifold design shown in FIG. 1, with the side elevation view being the same from all sides of the manifold. FIG. 4 is a top plan view of the circular seed distribution manifold design shown in FIG. 1; and,

FIG. 5 is a bottom plan view of the circular seed distribution manifold design shown in FIG. 1.

Structure, environment, and/or boundaries shown in broken lines form(s) no part of the claimed design.

Some aspects of the circular seed distribution manifold are shown with symbolic breaks in dimension: e.g., height, width. The appearance of any portion of the circular seed distribution manifold, between the break lines forms no part of the claimed design.
